UNITED STATES PATENT OFFICE.

RALEIGH B. BUZZAIRD, OF MAPLEWOOD, NEW JERSEY.

LOCK.

Application filed October 6, 1925. Serial No. 60,914.

This invention relates to locks in general, and more particularly to locks of the type employed for parcel lockers and the like.

One object of the invention is the provision of a lock which can be opened only by means of the key and is protected against pilfering.

Another object is the provision of a lock of the class more particularly referred to which can be opened only in a regular way by means of the key.

Another object is a lock of the type referred to in which simple means are provided for accurately registering the actual 15 periods of service.

Various other objects will be appreciated from the detailed description in connection with the accompanying drawings in which,

Fig. 1 is a rear view of a lock embodying 20 the invention;

Fig. 2 is a vertical section in a plane parallel to the face plate;

Fig. 3 is a view similar to Fig. 2 showing the elements of the operating mechanism 25 in a slightly different relative position;

Fig. 4 is a rear view of the device showing the elements of the operating mechanism in still another relative position;

Fig. 5 is a rear view showing the relative 30 position of the elements after the key is withdrawn;

Fig. 6 is a vertical section substantially on line 6—6, Fig. 1;

Fig. 7 is a horizontal section substantially 35 on line 7—7, Fig. 1;

Fig. 8 is a perspective view of a detail;

Fig. 9 is a fragmentary sectional view showing a relative position of certain elements as the result of an attempt to retract 40 the bolt in an irregular manner;

Fig. 10 is a perspective view of an important detail;

Fig. 11 is a fragmentary sectional view of another detail; and

45 Figs. 12, 13 and 14 are perspective views of various other detail mechanism.

In the drawings, 10 represents the face plate on the back of which all the operating mechanism is mounted, portions 10^a and 50 10^b thereof forming side flanges and 10^c a top flange.

The operating mechanism includes a key cylinder 11, a housing 12 therefor secured to the face plate by means of screws 14 passing 55 through lugs 13 extending laterally

from the housing. Adjacent the rear surface of the face plate the housing 12 is cut away to provide room for the pivotal movement of a lever 15 secured upon the cylinder 11 and moving therewith. The lever 15 60 has an upwardly extending arm 15^a engaging the bolt 16 and a downwardly extending arm 15^b engaging an auxiliary bolt 17.

Upon the back of the face plate 10 is also secured a member 18 defining a coin chute 65 19 at right angle to the face plate, the latter having a coin slot 20 through which the coins are entered into the coin chute. The upper portion of the coin chute is slightly inclined and has one of its walls offset to 70 define an inclined coin pocket 21 for a purpose to be more fully explained. In the walls of the coin chute between points near the upper end of the pocket 21 and points a distance below the pocket 21 are provided 75 elongated openings 22.

Upon the back of the face plate 10 is also pivotally mounted by means of a stud 23^a a plate 23 shown in detail in Fig. 13. This plate defines a downwardly extending arm 80 24 offset out of the plane of the plate to bring it into alignment with the openings 22, a tooth 24^a and a wing 25 acting as a shutter for the coin slot 20, the member 18 being cut away behind the face plate 10 to 85 make room for the plate 23 and permit angular movement thereof. Upon plate 23 are provided a stud 26 and a pin 27 for a purpose to be described later on.

The bolt 16 (shown in detail in Fig. 12) 90 is mounted for sliding movement by means of a stud 29 passing through a slot 30 in the bolt, the end of the bolt passing, as is usual, through an opening in the edge flange 10^a of the face plate.

The stud 29 extends beyond the bolt and serves as a pivot for a plate 32. The plate 32 is spaced from the bolt 16 by means of a spacer collar 33 and is held in position for free angular movement upon the stud 29 by 95 means of a collar 34, the arrangement being best shown in Fig. 6. The plate 32, which is shown in detail in Fig. 14, has a cam slot 35, a tooth 36 and a depending lug 37 defining a cam surface in conjunction with the lower edge of the cam slot 35. The plate 32 is acted upon by a coil spring 38 attached at its lower end to a stationary part, for instance a stationary pin 39 on the plate portion 12^a of the cylinder casing 12. A 100 105 110

coil spring 40 is attached at one end to a pin 41 on plate 32 and at its other end to the stud 26 on plate 23.

Upon the plate portion 12^a is slidably mounted a plate 42 which has in its lower portion a slot 43 through which extends a stud 44 which guides the plate 42 and holds it against the plate portion 12^a. A second slot 45 in plate 42 co-operates with a pin 46 to guide the plate 42 in vertical direction and limit the movement thereof in both directions. At its top the plate 42 has as a sliding surface the back of the counter 47 and is held thereto by means of a bridge 48 which is secured at one side to the side flange 10^a and has on its other side a fork 49 straddling the element 18 to hold it in proper position relatively to the coin slot 20. The bridge 48 preferably also has a slot 50 co-operating with a pin 51 on plate 42 to additionally guide the latter. The plate 42 is acted upon by a spring 52 mounted upon a pin 53 on the plate portion 12^a and bearing at its free end upon a stud 54 on the plate 42 while the other end of the spring is held stationary by engagement with the plate portion 12^a. The plate 42 thus tends to move to an upper position as limited by the pin 46 in slot 45, the upper position of the plate 42 being indicated in Fig. 5. The plate 42 has above its middle portion a cam slot 55 through which the stud 26 on plate 23 passes.

The arm 15^a of lever 15 carries at its upper end a pin 65, preferably of piano wire or the like, for co-operation with the cam surfaces of the lug 37 and the lower wall of cam slot 35 on plate 32.

The pin 27 in plate 23 is connected by means of a link 56 with the crank arm 57 of the counter 12.

The auxiliary bolt 17 is held for sliding movement by means of a strap 17^a and has also bearing in the side flange 10^a. A spring 58 which is connected at one end to a stationary part, for instance member 18, as shown, and at its other end to a lug 59 on the bolt 17 tends to hold the latter in retracted position. The bolt 17, shown in detail in Fig. 10, has a transverse notch 60 and a cam surface 61 extending from near the bottom of notch 60 to the upper surface of the bolt terminating close to the inner edge of the bolt. The arm 15^b of lever 15 carries at its lower end a pin 62 normally engaging in the notch 60. For reasons which will be more clearly understood as the description proceeds, the pin 62 is provided on a leaf spring 63 (Fig. 11) secured upon the rear surface of the arm 15^b.

The bolt 16 has on its upper face a cam surface 28 terminating in a slightly undercut shoulder 29 and on its lower portion a depending lug 31 and adjacent to it a recess 31^a into which the arm 15^b extends.

The operation of the device described is as follows:

Assume that the door of a locker is open and a party is about ready to close it. The bolt 16 is in retracted position and held in such position through the engagement of tooth 24^a on plate 23 with the shoulder 28^a on the bolt 16. This engagement is maintained through the action of spring 40 upon stud 26 and the action of spring 38 upon the plate 32 on which the pin 41 is carried.

In this position the key cannot be withdrawn and cannot be turned to operate the bolt. To do this it is necessary to drop a coin through the coin slot 20 into the chute 19. Fig. 1 shows the coin 64 just after it has been entered. It falls upon the arm 24 which is in its uppermost position, being a part of plate 23 which is under the influence of springs 40 and 38. The coin cannot remain in vertical position, due to the slight inclination of the wall of the chute at that point, but falls over on its side against the wall of the pocket 21 and comes to rest under the tooth 36 of plate 32 which is in alignment with openings 22. When the key is now turned to move the bolt to locking position, the pin 65 bears against the cam surface of lug 37 of plate 32 causing an angular movement thereof, whereby the tooth 36 forces the coin downwardly. This downward movement against the arm 24 causes a corresponding angular movement of plate 23 of which the tooth 24^a is a part. The tooth 24^a is thus raised out of engagement with the shoulder 28^a of the bolt 16 thereby releasing the bolt. Continued movement of the key, now causes the arm 15^a to project the bolt to locking position. As the bolt 16 moves outwardly the tooth 24^b is forced to ride up the cam surface 28 thereby angularly moving plate 23 about its pivot. This angular movement causes arm 24 to continue the downward movement initiated by the action of tooth 36 upon it through the medium of the coin.

At the end of the turning movement of the key to lock the bolt 16 the arm 24 has almost cleared the coin chute but still projects into it sufficiently to prevent the coin from passing by it. The bolt can be moved in and out to lock the door and to open it respectively, without danger of losing the service of the coin. This is of importance in practical use, because people are in the habit of closing the door only to open it again to take something out or to put something additional in. So long as the key is not pulled out they can safely operate the bolt without losing the service.

Now, when the bolt is finally shot, the key may be drawn out. This movement of the key is translated into movement of several elements, namely the movement of arm 24 to clear the coin chute, allowing the coin

to drop and to actuate the counter to register the service or the actual receipt of the coin. The key, as seen in Fig. 6, has at its end a bevel 66. During insertion of the key 5 the bevel 66 rides over the lower edge of an opening 67 in the plate 42 thereby causing downward movement of the same against the tension of spring 52. Conversely, when the key is pulled out, the plate 42 moves 10 upwardly under the influence of spring 52. As previously mentioned, the plate 42 has an opening 55 through which the stud 26 passes. This opening 55 is so shaped as to permit the stud 26 and plate 23 to angularly 15 move as described and has a cam surface which is immediately below the stud 26 when the bolt is in projected position. As the key is withdrawn and the plate 42 moves upwardly, the cam surface of the opening 20 55 moves the stud 26 laterally from the position shown in Fig. 4 to the position shown in Fig. 5, thereby imparting to the plate 23 a final angular movement as the continuation of the prior angular movements 25 described. This final movement causes arm 24 to completely clear the coin chute and also to complete an upward movement of the crank arm 57 of the counter, the initial movement thereof having been effected 30 during the angular movements of plate 23 caused first by the action of the coin and then by the action of cam surface 28 on bolt 16. Thus the counter 47 does not register the service until the key is pulled from 35 its normal position in the lock and retained as a check by the user.

When the bolt is projected, it may be retracted by means of the key to just clear the door and thereby permit opening thereof without retracting the bolt into its final position in which it would require the use 40 of a coin for further service. By such practice, it would therefore be possible to repeatedly use the locker without the deposition of coins.

It might also be possible to retract the bolt by means of knife blades entered into the narrow gap between the door and the jamb and work the blade into a position 45 whereby the door could be opened. This possibility would open the way for thieves to break into lockers.

In order to avoid illegitimate uses of the locker, such as mentioned, I have provided 50 the auxiliary bolt 17 and the means for correlating its movement with that of the main bolt 16 so that either one or the other is absolutely effective to prevent opening of the door except by means of the key operated in the normal way causing retraction of the bolt 16 to its final position in which further service can be had only by the deposit of another coin.

When the key is inserted to unlock the 55 door and then turned to retract the bolt from

the position shown in Fig. 4, the arm 15^a turns to the left, while the arm 15^b turns to the right, as seen from the back. While the bolt 16 is retracted, the auxiliary bolt 17 is projected into the jamb which has an 60 opening for the reception of it. Just as the bolt 16 reaches its final inward position, the pin 62, which has described an arc about the axis of the key cylinder as center, moves out of the notch 60 and the bolt 17 springs 65 back under the action of spring 58. Fig. 9 represents the relative position of the parts as the key approaches its final unlocking position. When this position is reached 70 the bolt 16 is withdrawn to such an extent that its end face is slightly within the outer surface of the side flange 10^a. The door thus cannot be opened until the key has been turned to the very end of its unlocking movement. However, when that final position 75 is reached, the auxiliary bolt 17 is also in retracted position and the door may be opened.

Suppose that a thief manages to retract the bolt 16 by means of knife blades as 80 above suggested, the inward motion of the bolt 16 is accompanied by an outward motion of the auxiliary bolt 17. The arrangement is such that the bolt 16 may be retracted until its end is flush with the outside 85 surface of the side flange 10^a without causing the release of the auxiliary bolt 17. A pilferer cannot possibly move the bolt 16 farther back than flush with the side flange 90 10^a and is thus unable to move it into such a position where the auxiliary bolt 17 is released. Since the two bolts are positively 95 interconnected, one of the two must always be in the jamb, except in the final unlocking position obtainable only in a regular way 100 by means of the key.

Figs. 1 and 2 show the relation of parts when the lock is unlocked. Locking movement of the key now causes the pin 62 to ride over the sharp edge defined by the 105 cam surface 61 at the upper face of the bolt 17 and over the cam surface 61 back into the notch 60.

To make it possible that the bolt 16 may be drawn an appreciable distance inwardly 110 of the outer surface of the side flange 10^a, the latter may be formed with inwardly deflected guide flanges 10^d indicated in Fig. 2.

While locks of the type described are, generally, well known and while I do not claim any novelty in regard to the broader aspects thereof, the device contains various specific features representing material improvements upon the prior art. Although these 120 improvements are specific in nature, there is considerable latitude in respect to the construction thereof. For this reason I do not intend to limit myself to the exact construction shown and described, it being under 125 130

stood that the latter illustrates merely what I consider a preferred embodiment of the invention.

I claim:

1. In a lock, the combination of a main bolt, an auxiliary bolt, key-actuated mechanism for concurrently operating the bolts in relatively opposite directions and means whereby the auxiliary bolt is automatically brought back into unlocking position when the main bolt is in final unlocking position.
2. In a lock, the combination of a main bolt, an auxiliary bolt, key-actuated mechanism for concurrently operating the bolts in relatively opposite directions and means co-operating with said key-actuated means for making the auxiliary bolt ineffective when the main bolt is in final unlocking position.
3. In a lock, the combination of a main bolt, an auxiliary bolt, key-actuated mechanism operative to positively move the main bolt and to concurrently move the auxiliary bolt in a relatively opposite direction in accordance with the main bolt during the greater part of the movement of the latter, said mechanism being constructed and arranged to make the movement of the auxiliary bolt independent of the movement of the main bolt when the latter is in final unlocking position, and spring means tending to maintain the auxiliary bolt in unlocking position.
4. In a lock, the combination of a main bolt, an auxiliary bolt, key-actuated mechanism for operating the main bolt, including means operative to move the auxiliary bolt from retracted position to locking position in accordance with the movement of the main bolt from locking position to unlocking position, said means being constructed and arranged to become ineffective when the main bolt has reached its final position during its unlocking movement and means for automatically returning the auxiliary bolt to unlocking position when said means has become ineffective.
5. In a lock, the combination of a main bolt, an auxiliary bolt, key-actuated mechanism including means for operating the main bolt and means operative to move the auxiliary bolt from unlocking position to locking position in accordance with the movement of the main bolt from locking position to unlocking position, and means tending to maintain the auxiliary bolt in unlocking position, the movement of the auxiliary bolt being independent of the main bolt when the latter is in final retracted position and during the movement thereof from unlocking position to locking position.
6. In a lock, the combination with a key cylinder and a counter, of means lying in the path of and operable by longitudinal movement of the key in the key cylinder to operate the counter.
7. In a lock, the combination with a key cylinder and a counter, of means lying in the path of and operable by longitudinal movement of the key in the key cylinder to operate the counter, said means including a movable member influenced by the movement of the key and spring means tending to move the said means against the action of the key.
8. In a lock, the combination with a key cylinder and a counter, of means operable by longitudinal movement of the key in the key cylinder to operate the counter, said means including a member slidably mounted in a plane intersecting the path of longitudinal movement of the key, means tending to maintain the said member in a definite position and means on the key and the said member whereby the latter is moved into or out of the definite position when the key is moved in longitudinal direction.
9. In a lock, a key cylinder, a counter, and means for actuating said counter, said means including a member lying in the path of and actuated by longitudinal movement of a key in the key cylinder.
10. In a key-controlled lock, means defining a passage for the reception of a key, a counter, and means for actuating said counter, said counter-actuating means including a member lying in the path of and actuated by longitudinal movement of a key in the said passage.

In testimony whereof, I affix my signature.

RALEIGH B. BUZZAIRD.
